TUBE FRAME CONTROL FOR AXMINSTER LOOMS

Filed Dec. 5, 1929

UNITED STATES PATENT OFFICE

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE FRAME CONTROL FOR AXMINSTER LOOMS

Application filed December 5, 1929. Serial No. 411,933.

This invention relates to improvements in Axminster looms and it is the general object of the invention to provide means to prevent relative movement of the tube frame with respect to its operating clutch after the latter has moved into disconnect the tube frame from the transporting chain and thus prevent low rows of piles.

Axminster looms usually operate with a pair of spaced transporting chains between which extend a series of tube frames carrying spools of variously colored pile yarns. These tube frames are presented to active position one at a time and are detached from the chains by a pair of transfer arms, one on each side of the loom. The arms carry clutches having pockets or seats in which the tube frames may rest, and the arms are moved by cams to lower the tube frame to present them to cloth forming position.

It occasionally happens that for one reason or another the tube frame will not become detached from its chain quickly enough to permit the same to move down instantly with its clutch, with the result that one or both ends of the tube frame will be raised. The arm moves through a fixed path so that the tube frame will not reach as low a point as it should. In the subsequent formation of tufts the lower end of the pile yarn extending from the tube frame forms one side of the U-shaped tuft, and if this end of the yarn starts from too high a position it is unable when combed into position to reach its proper level, thus causing low piles. If the tube frame sticks at both ends the low pile will extend across the rug, but if only one end sticks and the other end is properly released, the low piles will start at one side and will gradually disappear, the piles of the other side being of the required height.

It is an important object of my present invention to establish such connections between the clutches and the tube frame as will prevent the latter from having upward movement relatively to the clutch. If for any reason the tube frame cannot be detached from the chain the inability of the transfer arms to descend will bring about loom stoppage through well-known mechanism.

With these and other objects in view which will appear as the description proceeds, my invention resides in the combination and arrangement of parts hereinafter described and set forth in the claims.

In the accompanying drawings, wherein two forms of my invention are shown,

Fig. 1 is a front elevation of a portion of a tube frame and clutch made according to the preferred form of my present invention with the parts in the position they assume just prior to engagement of the clutch with the tube frame,

Fig. 2 is a view similar to Fig. 1 with certain parts shown in section and with the interengaging portions effective to prevent relative vertical motion of the clutch and tube frame,

Fig. 3 is a fragmentary perspective view of the clutch shown in Fig. 1,

Fig. 4 is an end elevation on a reduced scale taken in the direction of arrow 4, Fig. 1 showing the support and operating rod for the clutch,

Fig. 5 is a view similar to a portion of Fig. 2 but showing a modified form of the invention, and

Fig. 6 is a perspective view of the end of the tube frame such as shown in Fig. 5.

Referring to Figs. 1 to 4, where the preferred form of the invention is shown, I have illustrated a transporting chain 10 movable on sprockets one of which is designated at 11. The chain is provided with double links between which extends the tongue 12 of a tube frame bracket 13. A hook 14 may be pivotally mounted on one of the chain elements and have holding engagement with a portion of the bracket as set forth in Fig. 1. My invention is not limited to any particular form of hook.

The tube frame 15 may be formed of a hollow rectangular tubular bar having secured thereto the horizontal parallel arms 16 and 17 of the bracket 13. The arm 16 may if desired be integral with a spool bearing 18 on which is mounted the yarn carrying spool 19, while the other arm may be integral with the chain engaging finger 12.

The clutch which cooperates with the tube

frame is shown at 20 and comprises a vertical body 21 from the lower portion of which extends a lifting lip 22 having an inwardly and downwardly curved camming surface 23. The clutch is further provided with a supporting stud 24 extending through a carrier or transfer arm 25 as shown in Fig. 4. A second stud 26 is pivotally connected to a rocking rod 27 effective when the tube frame 10 is in lowered or cloth forming position to rock the tube frame and clutch around the stud 24 as an axis. Side wings 28 form with the lip 22 a pocket for the tube frame.

In carrying my present invention into effect I provide interengaging connections between the clutch and the tube frame effective to prevent improper positioning of the tube frame and clutch, and in the preferred form of the invention I provide the body of the clutch with a lug 30 which may project centrally between the side wings 28. I also provide the bracket 13 with an opening 31 proportioned to receive the lug 30. The distance from the bottom of the tube frame to the bottom of the opening 31 is approximately the same as the distance from the bottom supporting portion of the lip designated at 32 in Fig. 3 to the bottom of the lug.

In the modified form of the invention set forth in Figs. 5 and 6 I form a lug 40 on the bracket of the tube frame and form the clutch with a pocket 41. In this instance the distance between the bottom of the tube frame and the top of the lug 40 is substantially the same as the distance between the top wall of the pocket and the lip 22.

In operation, the clutch will be moved in toward the tube frame and engage the head of a depending hook 14 to move the same out 40 of holding engagement with the bracket after the camming lip 22 has passed under the adjacent end of the tube frame. The tube frame will move upwardly along the inclined surface 23 as the clutch continues its motion 45 and in this way entry of the lug 30 into the opening 31 or the lug 40 into the pocket 41 is effected. As previously described, the parts are so proportioned that the tube frame will be prevented from having a relative upward movement with respect to the clutch after the latter has been given its complete inward motion. It is to be understood that the operating parts of the loom which controls a clutch do not start the downward movement 50 of the latter until the clutch has substantially completed its motion toward the tube frame.

In the operation of my invention there is no opportunity for the tube frame to become displaced relatively to the clutch in a 60 vertical direction and it is therefore impossible to form low rows of piles such as may be produced by existing forms of clutch and tube frame. I am aware that it has been proposed heretofore to bring about stoppage 65 of the loom if the tube frame fails to move

down, this result being caused by cooperation between the clutch and the tube frame to hold the arm 25 in raised position. These previous constructions have been such as to permit an appreciable amount of downward motion on the part of the clutch in an attempt to dislodge the tube frame before the engagement referred to takes place. If during this short downward motion of the clutch the tube frame should become disengaged the latter will move toward the cloth in a somewhat tilted position. 70

From the foregoing it will be seen that I have provided simple means effective as soon as the clutch is properly positioned with respect to the tube frame and prior to its downward motion to prevent relative vertical motion between the tube frame and the clutch. It will also be seen that although my present invention is not aimed primarily to assist the 80 stop motion referred to but not shown herein, yet the lugs of either the preferred or modified form may act to effect loom stoppage if the tube frame sticks in the chain. The form of stop motion to which reference has been 85 made is shown in prior patent to Streimer No. 1,546,685. 90

Having thus described my invention it will be seen that changes and modifications may be made therein by those skilled in the art 95 without departing from the spirit and scope of the invention and I do not wish to be limited to the details herein disclosed, but what I claim is:

1. In an Axminster loom provided with a 100 clutch having first an inward and then a downward motion, a tube frame to be engaged by the clutch on the inward movement of the latter and supported thereby during the downward motion of the clutch, and interengaging elements formed on the tube frame and clutch to complete a positive connection to prevent relative upward motion of the tube frame with respect to the clutch during any portion of the downward motion 105 of the clutch. 110

2. In an Axminster loom provided with a clutch having first an inward and then a downward motion, a tube frame to be engaged by the clutch on the inward movement of the latter and supported thereby during the downward motion of the clutch, and interengaging connections between the clutch and tube frame effective upon completion of the inward motion of the clutch to prevent relative movement of the tube frame and clutch positively in all directions, said connections coacting prior to the downward motion of the clutch. 115

3. In an Axminster loom provided with a clutch having first an inward and then a downward motion, a tube frame to be engaged by the clutch on the inward movement of the latter and supported thereby during the downward motion of the clutch, interen- 120 125 130

- gaging connections between the clutch and tube frame which are brought into mutual engagement to form a positive connection between the clutch and tube frame during the inward motion of the clutch and become effective to prevent relative upward motion of the tube frame with respect to the clutch prior to the downward movement of the latter.
- 5 10. 4. In an Axminster loom having a tube frame member adapted to be moved from a supporting chain toward cloth forming position, a clutch member having an inward motion to release the tube frame from the chain and having a subsequent downward motion to move the tube frame toward cloth forming position, one of said members having an opening therein, and a projection extending from the other member to enter the opening during the inward movement of the clutch member to establish prior to the downward movement of the clutch member such connection between the members as will prevent relative movement between them.
- 15 20. 5. In an Axminster loom having a tube frame member adapted to be moved from a supporting chain toward cloth forming position, a clutch member having an inward motion to release the tube frame from the chain and having a subsequent downward motion to move the tube frame toward cloth forming position, a projection extending from one member movable into holding engagement with the other member during that motion of the clutch member which operates to release the tube frame from the chain, to prevent relative vertical motion of the members before the beginning of that motion of the clutch which moves the tube frame toward cloth forming position.
- 25 30. 40. In testimony whereof I have hereunto affixed my signature.

WILLIAM W. ROBERTSON.
